(57) **CLAIM**

The ornamental design for a front bumper portion, as shown and described.

DESCRIPTION

FIG. 1 is a front left top perspective view of a front bumper portion according to the present invention.

FIG. 2 is a front left perspective view of the front bumper portion shown in FIG. 1.

FIG. 3 is a rear right top perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front view of the front bumper portion with environment thereof.

The broken line showing of the vehicle is provided for the purpose illustrating environmental structure and forms no part of the claimed design.

1 Claim, 11 Drawing Sheets
